REVERSIBLE RED RIDING HOOD DOLL

Barbara J. Andrensen, 738 E. Palmaire,
Phoenix, Ariz. 85020

Filed Sept. 25, 1974, Ser. No. 509,094

Term of patent 14 years

Int. Cl. D21—01

U.S. Cl. D34—4 R

FIG. 4

FIG. 1 is a front view of a doll illustrating the Red Riding Hood and Grandma faces;

FIG. 2 is a partial side view of the upper torso of the Red Riding Hood portion;

FIG. 3 is a partial side view of the Grandma portion of the doll;

FIG. 4 is a full side view illustrating the dual face of the Grandma and Big Bad Wolf portion; and

FIG. 5 is a front view of the Big Bad Wolf face.

I claim:

The ornamental design for a reversible Red Riding Hood doll, as shown.
